UNITED STATES PATENT OFFICE.

ERNST LAUSCHKE, OF CHICAGO, ILLINOIS, ASSIGNOR TO BARNHART BROS.
& SPINDLER, OF SAME PLACE.

DESIGN FOR TYPE.

SPECIFICATION forming part of Design No. 18,971, dated March 19, 1889.

Application filed January 26, 1889., Serial No. 297,727. Term of patent 14 years.

To all whom it may concern:

Be it known that I, ERNST LAUSCHKE, a subject of the Emperor of Germany, residing at Chicago, county of Cook, and State of Illinois, have invented a new and original Design for a Font of Printing-Type, of which the following is a specification, reference being had to the accompanying typographical impressions, forming a part thereof.

This design comprises capital letters, figures, points, two ornaments, dollar-mark, and character &. In general character it is medium heavy faced, slightly extended, made up of lines of substantially uniform width throughout. It is characterized by the fact that the strictly horizontal lines are slightly narrower than the vertical or oblique lines, but not sufficiently so to present a contrast. This is noticed in the lines of A, B, C, D, J, O, P, Q, R, S, T, U, and Z, in the interrogation-point, dollar-mark, and all the figures. It is further characterized by the conjunction of that feature with the further feature that horizontal and vertical strokes, making junction in slightly-rounded corners rather than sharp angles, are employed in place of continuous ovals and circles in the letters C, D, G, O, Q, S, and U and several of the figures, the pe-

culiar effect of the design being due to the junction, in the manner described, of the horizontal and vertical lines of but slightly-different widths.

Another characteristic of the font is found in the letter G, whose finishing cross-stroke or horizontal characteristic extends wholly inward with respect to the letter, the angle, however, between said cross-stroke and the principal outline-stroke being finished with an acute ceriph pointing outward. The upper end of the final vertical strokes of H, N, and U and of the final oblique stroke of V, W, X, and Y are slightly concaved in an oblique direction with respect to the stroke and a fine point thrown off from the stroke transversely thereto as the finish of said concaved end. 45

I claim—

The design for a font of printing-type herein shown and described.

In testimony whereof I have hereunto set my hand, at Chicago, Illinois, this 12th day of January, 1889.

ERNST LAUSCHKE.
